UNITED STATES PATENT OFFICE.

WILLIAM B. HUGHES, OF CLEVELAND, OHIO.

FEEDING MECHANISM FOR GAS-PRODUCERS.

No. 904,873

Specification of Letters Patent.

Patented Nov. 24, 1908.

Application filed June 23, 1908. Serial No. 440,025.

To all whom it may concern:

Be it known that I, WILLIAM B. HUGHES, a citizen of the United States, residing in the city of Cleveland, county of Cuyahoga, 5 and State of Ohio, have invented certain improvements in Feeding Mechanisms.

This invention is a feeding mechanism designed primarily for delivering fuel to a gas producer, but it is also adapted for delivering ore and other substances.

It comprises means for propelling the coal or other substance to a device which picks it up and delivers it in a regular manner, the propelling means and delivering device operating in unison.

In the accompanying drawings, Figure 1 is a side view of apparatus embodying the invention; Fig. 2 is a vertical sectional view thereof; Fig. 3 is a sectional view taken on the line 3-3 of Fig. 2, and Fig. 4 is a sectional view taken on the line 4-4 of Fig. 2.

As illustrated, the mechanism comprises a fuel hopper 1 connected with a gas producer 2 by a conduit comprising the connected sections 3, 4, 5, and 6. In the preferred form shown, the section 3 drops from the hopper by a vertical course to the section 4 having a downwardly and laterally extending course to the section 5, which latter is in the form of a drum and delivers through the section 6 extending downwardly to the producer. In the section 4 there is located a propelling mechanism comprising a shaft 7, journaled in bearings 8, and arms 9 extending from the shaft, the latter having fixed thereon a spur gear 10. In the section 5, there is located a delivering mechanism comprising a shaft 11, journaled in bearings 12, and fixed thereon a bucket wheel or segmental drum 13 containing the pockets 14, the shaft 11 having fixed thereon a pinion 15 which meshes with the gear 10. A ratchet wheel 16 is fixed to the shaft 11 and loosely mounted on the shaft is the arm 17 which carries a pawl 18 engaging the ratchet wheel. The arm 17 may be oscillated, to operate the ratchet mechanism and revolve the bucket wheel, by means of a rod 19 which connects it with a crank lever 20 adapted to rock in the bearing 21, and a rod 22 connected with the crank lever. The reverse movement of the bucket wheel is prevented by the engagement of a gravity pawl 23 with the ratchet wheel. The pawl 18, normally held by gravity in engagement with the ratchet wheel, may be disengaged,

to prevent the revolution of the bucket wheel with the oscillation of the arm, by a finger 24 on an arm 25, a pin 26 holding up the arm when it is desired to withdraw the finger from the pawl. A finger 27, fixed to the shaft 11, makes contact with the star wheel 28 of an indicator 29 by which the amount of material passed by the bucket wheel may be determined.

In operation, the solid substance flowing from the hopper 1 through the vertical conduit section 3 falls upon the inclined bottom section 4' and is checked by the flatter bottom section 4'' of the conduit section 4, the course being of such character that the surface of repose of the substance will approximate the axis of the propeller. The revolution of the propeller in unison with the bucket wheel causes the former to move the substance at the desired rate to the latter. The buckets pick up the substance as they pass the outlet from the section 4 to the section 5, being moved upwardly in the direction of the arrow, so that the substance is lifted up from its natural course of gravitation, with avoidance of the wedging or binding action by the substance, between the rear wall of the bucket and the angle of the conduit bottom, which would take place in revolving in the opposite direction. As the buckets pass the conduit section 6 they deliver therethrough to the body 2.

Having described my invention, I claim:

1. In apparatus of the class described, feeding mechanism comprising a conduit, a propelling device, and a revolving device having pockets charged by the action of said propelling device.

2. In apparatus of the class described, feeding mechanism comprising a conduit, a revolving propelling device, a second revolving device having pockets charged under control of the action of said first revolving device, and means whereby said devices are operated in unison.

3. In apparatus of the class described, feeding mechanism comprising a conduit, a revolving propelling device, a revolving device having pockets charged as they move upwardly, and means for revolving said devices.

4. In apparatus of the class described, mechanism comprising a conduit having a laterally extending section and a cylindrical section, a shaft having propelling means revolving in said laterally extending section,

a segmental drum having pockets revolving in said cylindrical section, and means for operating said revolving parts together.

5. In apparatus of the class described, 5 mechanism comprising a laterally extending section and a cylindrical section to which said laterally extending section delivers, a revoluble shaft having arms in said laterally extending section, a revoluble segmental drum having pockets in said cylindrical section, and means for operating said drum so that its pockets move upwardly in passing said laterally extending section.

6. In apparatus of the class described, 15 mechanism comprising a conduit, a revoluble shaft having thereon arms acting in a section of said conduit, a revoluble shaft having thereon pockets acting in a second section of said conduit, engaging gear 20 wheels on the respective shafts, and indicating mechanism operated by the movement of said revolving parts.

7. In apparatus of the class described, 25 mechanism comprising a conduit having a section with a downwardly and laterally ex-

tending bottom and a cylindrical section connected therewith, a journaled shaft having thereon arms in said first named section, a gear wheel on said shaft, a journaled shaft having thereon a segmental drum with 30 pockets in said cylindrical section, a gear wheel on said shaft last named, said gear wheels being in engagement, and means for actuating said revoluble parts.

8. In apparatus of the class described, 35 a hopper, a conduit leading therefrom, a journaled shaft having arms revoluble in said conduit, a journaled shaft carrying pockets revoluble in said conduit, engaging gear wheels on the respective shafts, a pawl and 40 ratchet mechanism connected with one of said shafts, and means for operating said pawl and ratchet mechanism.

In witness whereof, I have hereunto set my name this 13th day of June, A. D. 1908, 45 in the presence of the subscribing witnesses.

WILLIAM B. HUGHES.
